LOCK FOR SECTIONAL, FOLDING TABLE TOPS

Robert L. Norris, Jr., Sacramento, Calif.

Application September 12, 1952, Serial No. 309,291

1 Claim. (Cl. 311—19)

1

This invention relates to a lock for a collapsible, wall-mounted, folding table of sectional design.

Among the important objects of the invention are the following:

To provide a lock of the type stated which will be safe in operation, simple in construction, and easily manipulated to locking and unlocking positions respectively;

Second, to provide a lock which will be effectively concealed in both the locking and unlocking positions thereof;

Third, to provide a lock so designed as to effectively hold a pair of hinged leaves of a table against relative movement, when said leaves are in a coplanar, extended position;

Fourth, to provide a locking device for tables of the type stated, which will be so designed as to permit a folding or collapsible table to be made without more than a single supporting leg; and

Fifth, to provide a lock of the type stated which can be manufactured separately from a table with which it is to be associated, at relatively low cost, said lock being so designed as to permit it to be installed quickly and easily in a table of the sectional, folding type.

Other objects will appear from the following description, the claims appended thereto, and from the annexed drawing, in which like reference characters designate like parts throughout the several views, and wherein:

Figure 1 is a top plan view of a table formed with hinged leaves, said leaves being shown in their extended position, part of the leaves being shown in section to illustrate, in top plan, a locking device formed in accordance with the present invention;

Figure 2 is a side elevational view of the extended table and of the locking device constituting the present invention;

Figure 3 is a view similar to Figure 2, in which the table is shown in its folded position; and

Figure 4 is an enlarged perspective view of the locking device per se.

Referring to the drawing in detail, the reference numeral 10 has been applied to the flat, rectangular, inner leaf of sectional, wall-mounted, collapsible table. The inner leaf 10 is connected, along one edge thereof, to a wall surface W, by hinges 12, said hinges being adapted to permit the inner leaf to swing between a vertical position shown in Figure 3 and a horizontal position shown in Figure 2.

An outer leaf 14 is also of rectangular configuration in the illustrated embodiment of the

invention, said outer leaf being connected, along its inner end edge, to the adjacent edge of the inner leaf 10, by concealed hinges, not shown. It will be understood that when the inner leaf 10 is swung to its vertical, inoperative position shown in Figure 3, the outer leaf 14 is swung upwardly to a vertical position (see Figure 3). When, however, the table is to be used, the outer leaf 14 swings to a position in which it is coplanar with the inner leaf 10.

A single leg 16 is hingedly connected, by hinges 18, to the underside of the outer leaf 14, and when the leg 16 is swung away from the outer leaf 14, it will support the table in a horizontal, operative position.

The device constituting the present invention has been illustrated per se in Figure 4, and is mountable in slots 20, 22 of the leaves 10, 14. It may be noted, at this point, that identical but opposite locking devices can be used, and preferably would be used, at opposite sides of the table. Since these devices are like one another in construction, only one shall be described herein.

The slot 20 of the inner leaf 10 extends along one side edge of the inner leaf, opening at one end upon the end edge of the inner leaf, which end edge is hingedly connected to the adjacent end edge of the outer leaf 14. Slot 20 extends longitudinally of said side edge of the inner leaf 10, and when the leaves 10, 14 are in their coplanar, operative positions, the slot 20 is in communication with a slot 22 formed in the corresponding side edge of the outer leaf 14.

Within the slot 20 there is mounted a pivot pin 24, said pivot pin being extended between the top and bottom walls of said slot 20, and being passed through one end of an elongated, flat lock bar 26.

The lock bar 26 is thus mounted for swinging movement within the slot 20, and in one position to which the lock bar 26 is swung, it will extend across the hinged leaves 10, 14, into the slot 22.

As a result, the leaves 10, 14 will be locked in their operative, extended positions.

A finger grip 28 is provided upon the lock bar 26, said finger grip 28 being formed as a member of right angled configuration, one leg of said member overlying the top surface of the lock bar 26, and being pivotally connected to said lock bar by means of a rivet or pivot pin 30.

The other or free leg of the finger grip 28 is extended transversely of and beyond the edge of the lock bar 26.

In this connection, the adjacent end of the lock bar 26 is rounded off, and thus, the finger grip 28 can be swung about said rounded end of the lock bar, to opposite sides of the lock bar.

It will thus be seen that when the lock bar is in the position thereof shown in Figures 1 and 2, the finger grip 28 will be disposed exteriorly of the slots 20, 22, and can be readily grasped by a user. Thus, one grasping the free leg of the grip 28 can swing the same outwardly, thus to cause the leg 26 to move out of the slots 20, 22. This permits the leaves 10, 14 to be unlocked, thus to permit said leaves to be swung to their folded positions, shown in Figure 3.

When the lock bar 26 is swung to its inoperative position, the finger grip 28 can be swung about the axis of the pivot pin 30, to the opposite side of the lock bar, and thus will still be disposed exteriorly of the slot 20 (see Figure 3) in the inoperative position of the lock bar. This permits the user to swiftly grasp the lock bar once again, when the bar is to be used in latching the leaves 10, 14 against relative swinging movement.

The construction which has been illustrated and described is believed to have certain important characteristics, which may be worthy of note herein. The arrangement is such as to securely lock the leaves 10, 14 together, to form a rigid table which can be easily supported on a single leg 16.

Additionally, the locking means is such as to be invisible when the table is viewed from above, except, of course, for the small projections represented by the finger grips 28.

Still further, the construction is such as to permit the device to be readily mounted in a table of the type stated, at a minimum of expense and with minimum loss of time. The device could, in fact, in commercial embodiments of the invention, be manufactured separately from the tables, with a housing of its own, which housing would provide the slots 20, 22.

It is believed apparent that the invention is not to be confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

15 A table top comprising a pair of leaves, hinges coupling adjacent edges of the leaves for enabling said leaves to be folded into superposed relation, said leaves having grooves extending into opposite side edges and opening through the hinged edges of the leaves, a bar pivotally mounted adjacent one end in each groove in one of the leaves, said bars being movable in arcuate paths which lie parallel to the leaf in which the bars are pivoted from an inactive position in which they lie wholly within the grooves to an active position in which they extend through the ends of the grooves and into the grooves in the adjacent leaf, and finger holds pivotally carried by the bars for movement about the ends thereof remote from their pivoted ends.
